UNITED STATES PATENT OFFICE.

THOMAS MALCOLMSON, OF OIL CITY, PENNSYLVANIA, ASSIGNOR OF ONE-HALF TO OCTAVIUS B. GOODWIN, OF SAME PLACE.

STEAM-GOVERNOR.

SPECIFICATION forming part of Letters Patent No. 289,428, dated December 4, 1883.

Application filed June 23, 1883. (No model.)

To all whom it may concern:

Be it known that I, THOMAS MALCOLMSON, a citizen of the United States, residing at Oil City, in the county of Venango and State of Pennsylvania, have invented certain new and useful Improvements in Steam-Governors, of which the following is a specification, reference being had therein to the accompanying drawings, in which—

10 Figure 1 is a perspective of a steam-governor constructed in accordance with my invention. Fig. 2 is a central vertical section, and Fig. 3 a transverse section, of the same.

Like letters indicate like parts in all the figures.

15 The invention herein disclosed is an improvement of that shown in a companion application, No. 84,329, filed by me and now pending, in which certain features shown and 20 not claimed are now claimed.

25 The object of the present invention is to provide means whereby increase or decrease of the speed of an engine shall automatically vary the supply of steam to the same, so that the operation shall be uniform under varying 30 loads, and to accomplish this by simple, servicable, and sensitive devices, wherein centrifugal force acting against the tension of springs shall overcome said tension and liber- 35 ate a counter balance to effect, by suitable connecting mechanism, a variation in the supply of steam. Other objects and advantages will appear in the following description:

40 A represents the valve-chamber, which contains what is generally designated an "oscillating valve," and is connected with the cylinder of an engine in such manner as to control the admission of steam therein to operate the piston, these parts being of any well-known construction.

45 B represents the valve-rod, which is provided with an arm, B', connected to a post, B'', projecting from the face of a disk, C, mounted loosely upon a shaft, D, supported in a bracket, E, formed on or secured to the head of the valve-chamber A. A' is the ordinary stuffing-box for the valve-rod B. The shaft D is hollow throughout the greater portion of its length, and is provided with an oil-cup, D', 50 communicating with its interior, and with apertures filled with wooden plugs d, by which

means the bearing-surfaces of said shafts and an enveloping-sleeve, F, are lubricated, all as described and claimed in said companion application.

55 Rigidly secured to or formed on the sleeve F is a disk, G, having a flange, g, which encompasses the disk C, forming an annular space thereabout, as clearly shown in Fig. 3. A pulley, F', is also rigidly mounted on the 60 sleeve, which pulley, by means of the usual governor-belt, is rotated so as to revolve the sleeve and the disk G.

Upon the inner wall of the flange g are secured the ends of springs H, in this instance 65 two in number; but, if desired, more may be employed.

To the free ends of the springs are secured 70 weights I, with or without, as desired, friction pads or cushions i. The springs H are 75 constructed and arranged to normally hold the weights against the periphery of the inner disk, C, with a predetermined pressure, and for this purpose the two screws i, i' may serve as means of adjusting the degree of pressure 80 exerted by driving in the inner screw, i', more or less.

An arm, J, is secured to and projects from 85 the disk C, and is provided with an adjustable weight, K, and a stop, L, projects from the face of the disk in such a position as to permit a slight rotation thereof in both directions, the rotations being limited by the interposition between the stop L and the port B' and arm B of one branch or portion of the 90 bracket D.

The operation is as follows: The disk G, being rotated as described and in the direction indicated by the arrows, will, when the speed of its rotation is normal, simply rotate the 95 disk C in the same direction and to such a distance that the arm B' rests against the bracket E, as clearly shown in Fig. 1. Now, if the speed of the engine, from any cause, is increased—say slightly and momentarily—the 100 arm B' may alternately recede from and approach the bracket; or, in other words, may partake of a slight oscillatory movement by reason of the momentary decrease of pressure of the weights on the disk; but should the speed be increased to a marked degree, then centrifugal force operates in the weights I to over-

come the tension of the springs, and the friction of the weights being thus removed from the disk C, the weight K acts by gravity to rotate the disk C in the opposite direction, 5 and this movement of the disk, through the medium of the post B² and arm B', turns the valve-rod B and cuts off the supply of steam, and hence reduces the speed of the engine, which in turn reduces the centrifugal force in 10 the weights, and they, by the tension of the springs, are again brought into contact with the disk C, which is carried forward to the first position to automatically operate, as described. In this manner a very sensitive control 15 of the steam-supply is secured.

It will be observed that in case of any accidental breakage, running off, or other disconnections of the governor-belt from the pulley F', all resistance to the gravity of the weight 20 K is removed, and hence it automatically, and through the connecting means shown and described, operates the valve-rod B and the valve thereto attached, so as to shut off the supply of steam, whereby the engine is stopped 25 without the necessity of employing extraneous or other devices for that purpose.

Having described my invention and its operation, what I claim as new, and wish to secure by Letters Patent, is—

30 1. In a steam-governor, an inner and an outer disk, the latter carrying spring-seated weights bearing upon the inner disk, which is connected with the valve-stem and provided with a counter-balance, substantially as specified.

35

2. The combination of an outer continuously-rotatable disk, an inner oscillatory disk, springs secured to the former and bearing upon the latter, and means for varying the tension of the springs, substantially as specified. 40

3. The combination of the valve-chamber, a bracket secured thereto, shaft D, carrying disk C, its surrounding disk G, springs secured to the latter, and having weights I, with means for limiting the movement of disk C in 45 one direction, and means for giving it a movement in an opposite direction, substantially as specified.

4. The combination of the outer disk, G, having flange g, springs H, and weights thereon, with disk C, having stop L and counter-weight K, and with valve-stem B and bracket, substantially as shown and described. 50

5. The combination of bracket E, shaft D, its sleeve and pulley, with disks G and C, 55 weighted springs, arm B', rod B, arm J, and weight K, secured to the inner disk, substantially as shown and described.

6. The combination of an outer disk carrying spring-seated weights adapted to be operated by a governor-belt, with an inner disk connected with a valve-stem and provided with a counter-balance, substantially as and for the purpose specified. 60

In testimony whereof I affix my signature in 65 presence of two witnesses.

THOMAS MALCOLMSON.
